(57) CLAIM

(51) LOC (7) Cl. **13-03**

The ornamental design for a knurled sleeve for co-axial
cable connector in open position, as shown and described.

(52) U.S. Cl. **D13/154**

DESCRIPTION

(58) Field of Search D13/133, 149,
D13/151, 154; 439/578, 583, 584, 585

(56) **References Cited**

FIG. 1 is a perspective view of a knurled sleeve for co-axial
cable connector in open position showing my new design.
FIG. 2 is a side elevational view thereof all other sides, top
and bottom plan views being identical thereto;
FIG. 3 is a nut view thereof; and,
FIG. 4 is a cable end view thereof.

The broken lines in the drawings depict environmental
structure, which forms no part of the claimed design.
